(57) **CLAIM**

The ornamental design for a device for installing and removing plastic covers for studs and nuts of truck wheels, as shown and described.

DESCRIPTION

FIG. 1 is a bottom perspective view of a device for installing and removing plastic covers for studs and nuts of truck wheels showing my new design;

FIG. 2 is a top perspective view thereof;

FIG. 3 is a front and back elevation view thereof;

FIG. 4 is a left and right side elevation view thereof;

FIG. 5 is a top view thereof;

FIG. 6 is a bottom view thereof; and,

FIG. 7 is a sectional view taken along line 7-7 of FIG. 5. The broken line showing of details in FIGS. 6 and 7 is included for the purpose of showing a fastening screw and forms no part of the claimed invention.
